United States Patent

Des. 238,811
Patented Feb. 10, 1976

238,811

PIN

Hilary H. Ziglar, 6148 Dilbeck Lane 75240; Melvin R. Carter, 9437 Brentgate Drive 75238; and Libby S. Daniels, 3417 St. Johns Drive 75205, all of Dallas, Tex.

Filed Mar. 11, 1974, Ser. No. 450,124

Term of patent 14 years

Int. Cl. D11—01

U.S. Cl. D45—19 N

FIG. 1

FIG. 2

FIG. 3

FIG. 4

FIG. 1 is a front elevational view of a pin showing our new design;

FIG. 2 is an end elevational view thereof as viewed from the right hand end of FIG. 1;

FIG. 3 is a top plan view thereof; and

FIG. 4 is a rear elevational view of the pin of our invention.

We claim:

The ornamental design for a pin, substantially as shown.
